EDWARD A. LANGTON, OF NEW YORK, N. Y., ASSIGNOR OF ONE-HALF TO CHARLES T. HAYNER, OF NEW YORK, N. Y.

NON-REFILLABLE BOTTLE.

1,047,662.

Specification of Letters Patent.

Patented Dec. 17, 1912.

Application filed March 5, 1912. Serial No. 681,714.

To all whom it may concern:

Be it known that I, EDWARD A. LANGTON, a citizen of the United States, and residing at New York, in the county of New York and State of New York, have invented certain new and useful Improvements in Non-Refillable Bottles, of which the following is a specification, such as will enable those skilled in the art to which it appertains to make and use the same.

This invention relates to bottles, jugs, jars, and similar vessels and the object thereof is to provide a vessel of this class which having been once filled and emptied of its contents cannot be refilled or reused.

The invention is fully disclosed in the following specification of which the accompanying drawing forms a part, in which the separate parts of my improvement are designated by suitable reference characters in each of the views, and in which;

Figure 1 is a central sectional view of the neck portion of a bottle involving my invention; Fig. 2 a similar view showing the bottle inverted or tilted as in the operation of pouring out the contents thereof; and Fig. 3 a cross section on the line 3—3 of Fig. 1.

In the drawing forming part of this specification I have shown at *a* the top part of a bottle provided with a neck *a*² of the usual general form and in the bottom portion of which is an inner annular valve seat *b*. At a predetermined distance above the valve seat *b* is placed a two part collar or plug *c* preferably supported on an annular ledge or shoulder *b*³ formed in the neck of the bottle, and I also provide a valve *d* which is preferably conical in form, and the smaller end of which is directed downwardly, and said valve is adapted to be seated on the valve seat *b* and to close the passage through the neck *a*². The valve *d* is provided with a shank *d*² which passes loosely through the collar or plug *c*, and which is provided at its upper end with a stopper *d*³ having a head *d*⁴, the stopper *d*³ being designed to close the neck of the bottle, and the head *d*⁴ to rest on the top thereof, and to form a handle for the stopper. The stopper *d*³ is slightly tapered as is also that part of the neck in which said stopper fits, and in practice the stopper *d*³ is ground so as to produce a tight fit. The valve *d*, the shank *d*² thereof, the stopper *d*³, and the head *d*⁴ of the stopper are all formed integrally and preferably of

glass, porcelain or similar material, and the collar or plug *c* is also composed of similar material, and said collar or plug is provided in the bottom thereof with V-shaped recesses *c*² to prevent the valve *d* from closing the passage through said plug when the parts are in the position shown in Fig. 2.

The operation will be as follows; In practice the bottle is first filled with the desired liquid after which the collar or plug *c* is placed on the shank of the valve, and said valve, the collar or plug, and the stopper *d*³ are inserted into the neck of the bottle, and in this operation glass cement, or other suitable cement, is placed on the collar or plug *c*, and when it has been forced into the neck of the bottle in the manner above described, and said cement has had time to set or become hard, the said collar or plug cannot be removed from the neck of the bottle and all the parts of the attachment are permanently connected therewith.

It is desirable to have a slight space between the stopper *d*³ and the collar or plug *c* and in order to provide for this the said stopper is provided at the bottom thereof with small projections *e*, or said projections may be formed on the top of the collar or plug *c*.

When the parts of the attachment have been secured in the neck of the bottle, the valve *d* the shank *d*², and the stopper *d*³ will be capable of slight longitudinal movement, and when it is desired to empty or discharge a portion of its contents, the stopper *d*³ is loosened by means of the head *d*⁴ thereof and the bottle is inverted or tilted as shown in Fig. 2, and the contents thereof will flow out as indicated by the arrows *a*, and this operation may be continued or repeated until the bottle is entirely emptied.

If an attempt be made to refill the bottle by holding it in an upright position and pouring liquids therein to the valve *d* and its connected parts will drop into the position shown in Fig. 1, and no liquid can enter the bottle. If an attempt be made to pour liquids into the bottle while holding the valve and stopper *d*³ in a raised position a slight amount of liquids can thus be made to enter the bottle, but the amount will be so small that it will take so long to get an appreciable amount of liquids into the bottle that this effort could not be made a success. If an attempt be made to refill the

bottle by inverting it in a tub or vessel full of liquid the result will be the same as the last above set out. It must be understood that in each case the air must leave the bottle as the liquid enters it, and by reason of the passages in the neck being so small this operation, when an attempt to refill the bottle by either of these processes, would be to all intents and purposes a failure.

10 Having fully described my invention what I claim and desire to secure by Letters Patent is:—

15 A bottle or similar article having a neck, reduced at its lower extremity to form a valve seat, and being provided at a point between said valve seat and its upper extremity with a plug having an opening

therethrough, said plug being located at a distance from the mouth of the bottle and being adapted to be permanently secured therein, a valve stem mounted loosely in said opening, provided at one end with a valve and at the other end with a bottle stopper having an enlarged head extending above the neck.

25

In testimony that I claim the foregoing as my invention I have signed my name in presence of the subscribing witnesses this 4th day of March 1912.

EDWARD A. LANGTON.
